J. LALLY

CAP FOR BUILDING COLUMNS

Filed March 24, 1923

FIG. 1

FIG. 2

FIG. 3

INVENTOR
John Lally
BY
Robert B. Killgore
ATTORNEY

UNITED STATES PATENT OFFICE.

JOHN LALLY, OF BOSTON, MASSACHUSETTS.

CAP FOR BUILDING COLUMNS.

Application filed March 24, 1923. Serial No. 627,412.

To all whom it may concern:

Be it known that I, JOHN LALLY, a citizen of the United States, residing at Boston, Suffolk County, Massachusetts, have invented certain new and useful Improvements in Caps for Building Columns, of which the following is a specification.

My invention relates to caps for building columns and it is my object to produce a sheet steel cap cheaply which will carry all reasonable loads and not tend to slide off the column end under load and in which I utilize the ductility of sheet steel for the holding portion of the cap and steel plate for the load carrying portion.

In the drawing Fig. 1 is a top view of my cap on a column, partly in section; Fig. 2 a side view of the structure of Fig. 1, partly in section; and Fig. 3 a sectional view of a slight modification of the cap.

The column is the usual steel tube 1 with the filling of concrete 2.

The cap consists of a relatively thin sheet steel plate 3 having a retaining bead 4 pressed therein by dies which displace a portion of the plate beyond its surface, the bead being approximately a fit for the casing end. As shown in Figs. 1 and 2 this bead 4 is a fit for the outside of the casing 1.

A second, relatively heavy piece of sheet steel plate 5 for load carrying purposes is laid on the sheet 3 carrying the bead 4 and the two are secured together, spot welding 6-6 being preferably employed.

As the retaining bead could not be pressed from a single thickness of sheet steel plate which would be heavy enough for load carrying purposes I have adopted the lami-

nated construction for the cap for by this construction the retaining bead is easily 40 pressed into the thinner metal and the heavier metal being after united thereto gives the necessary strength for load carrying.

In use the laminated cap is laid on the column end and the retaining bead prevents slipping. If desired the laminated cap may be further secured to the casing, concrete or both in any desired manner.

In Fig. 3 I have shown a slight modification in which the retaining ring 4' in the thinner sheet 3' is located inside the casing 1, the heavier plate 5' being secured to the plate 3' by spot welding 6-6' as in the other form shown.

By selecting different grades of steel a very ductile sheet may be used for the stamped sheet and a more rigid and resisting sheet for load carrying purposes.

I claim:—

1. A cap for building columns comprising a relatively ductile plate of metal adapted to rest on a column end with a portion thereof displaced beyond the surface, said displaced portion being adapted to engage a 65 column end and a second, rigid plate secured thereto.

2. A cap for building columns comprising a plate of metal having a retaining bead pressed therein, said bead being adapted to 70 engage the side walls of a column end, and a second plate of metal secured thereto for load carrying purposes.

In testimony whereof I have hereunto subscribed my name.

JOHN LALLY.
